CLASP

Michel Barmache, New York, N. Y.

Application June 8, 1934, Serial No. 729,683

5 Claims. (Cl. 24—81)

This invention relates to clasps and more especially the combination clasps that comprise two gripping elements, the object of the invention being to provide a clasp member adapted to be attached to an article of clothing and having a second clasp hinged to the first and hidden by a broach or other ornament and adapted to hold flowers, ribbons or other ornaments.

These and other objects and details of the invention are more fully described in the following specification, set forth in the appended claims and illustrated in the accompanying drawing, wherein:

Figure 1 is an outer view of the improved clasp and broach.

Fig. 2 is a side elevation of the clasps closed.

Fig. 3 is a similar view of the same when opened.

Fig. 4 is a rear view of the complete clasp.

Fig. 5 is a rear view of the device with the attaching clasp removed.

Fig. 6 is a similar view with both clasps removed from the broach.

Fig. 7 is a perspective view of the second clasp removed from the broach.

Fig. 8 is a perspective view of a modified form of the attaching clasp.

Fig. 9 is a side elevation of the complete modified device.

Fig. 10 is a sectional detail showing the latch.

Fig. 11 is a detail view showing the modified pin fastener.

In actual use the clasp may be given the appearance of a handsome broach of precious metal and decorated with gems and that part only showing that appears as a broach 10 but the latter may be termed a base and has at its lower end the hinge member 11 and at its upper end the latch 12, more fully shown in Fig. 10, by which the clasps are secured.

Hinged to the member 11 is a frame 13 having guideways 14 into which is adapted to be inserted a sliding sash 15 and both the frame 13 and the sash 15 have spurs 16 on their inner faces to more firmly grasp any substance held by them.

The sash 15 has at its lower outer end a spur 16' and at its upper inner end the hook 17 that is caught by the plunger 18 of the latch 12 and holds itself and the member 13 against the broach 10. The sash also has side flanges to fit in the guide-ways of the member 11.

To the upper end of the sash 15 is hinged a second frame or clasp member 19 having a spring 20 that fits against the squared head 21 of the sash 15 to hold the clasp member 19 either in its closed relation as shown in Fig. 2 or in its open position as shown in Figs. 3 and 7. This member also has spurs 16 on its inner face and a lip 22 on its lower end to open or close it.

As the member 19 and sash 15 may be removed

from the frame 13 it will be possible to substitute a sash 23 therefor with a pin 24 that may attach the device to a fabric instead of by use of the clasp member 19, and as shown in Figs. 8 and 9, where it is shown inserted partially and fully in the hinged member. The pin 24 may be also secured by a catch best shown in Fig. 11 to lock it to a garment and prevent the loss of the device.

While the device is thus initially secured to a garment the space between the broach 10 and the hinged member 13 may be used to clasp drapery, flowers or other decorations used on the garment and the hook 17 and the latch 12 hold the combined clasps together and insure safety of the parts from detachment and loss.

It is obvious that the parts may be otherwise arranged or modified without departing from the essential features above described or from the scope of the appended claims.

What I claim as new is:

1. In clasps, the combination of a base member, a clasp member hinged to said base member, and a second clasp member and adapted to fold down on the same slidably connected with the first clasp member.

2. In clasps, the combination of a base member, a clasp member hinged to the same, and a second clasp member connected with the first member by a slide and adapted to open and close, all of the said members being adapted to fold down on each other.

3. In clasps, the combination of a base member, a clasp member hinged to the base member, a sliding sash in the said clasp member, a second clasp member hinged to the said sash, and locking means securing the clasp members when closed to the base member.

4. In clasps, the combination of a base member comprising a broach, a frame having frictional securing means and hinged to the base, a sash adapted to be slid in guide ways in said frame, a latch in the base member, a hook carried by the sash and adapted to be engaged by the latch, and clasping means hinged to the sash.

5. In clasps, the combination of a broach, a frame having guide-ways and hinged to the broach, a clasp member adapted to be slid in the guide-ways, a cooperating clasp member hinged to the first-mentioned clasp member, a spring controlling the hinged relation of the clasp members, and locking means connecting the said clasp members to the broach.

MICHEL BARMACHE.
